UNITED STATES PATENT OFFICE.

CHARLES W. LOGAN, OF KENMORE, NEW YORK, ASSIGNOR, BY MESNE ASSIGNMENTS, TO MARKEL ELECTRIC PRODUCTS, INC., OF BUFFALO, NEW YORK, A CORPORATION OF NEW YORK.

DESIGN FOR AN ELECTRIC-LIGHT FIXTURE.

Application filed December 4, 1926. Serial No. 19,927. Term of patent 3½ years.

To all whom it may concern:

Be it known that I, CHARLES W. LOGAN, a citizen of the United States, residing at Kenmore, in the county of Erie and State of New York, have invented a new, original, and ornamental Design for Electric-Light Fixtures, of which the following is a specification, reference being had to the accompanying drawings, forming part thereof.

In said drawings:

Figure 1 is a side elevation of an electric light fixture showing my new design, half of

the figure showing the ornamentation in detail and the remaining half being in outline to indicate repetition of the ornamentation.

Figure 2 is a bottom plan view of the same, partly in detail and partly in outline, the part shown in outline involving repetition of the detail.

I claim:

The ornamental design for an electric-light fixture, as shown.

CHARLES W. LOGAN.
